G. Kennedy

Attorney

UNITED STATES PATENT OFFICE.

WILLIAM HUSMAN, OF LA PORTE CITY, IOWA.

MOTOR GOVERNOR.

Application filed January 31, 1927. Serial No. 165,014.

My invention relates to improvements in motor governors, and the object of my improvement is to supply auxiliary means for automatically governing the fuel supply delivered to the inlet manifold of an internal combustion engine, so that the speed of the engine may be properly regulated, especially when it is used for the operation of machinery, and particularly when the engine is 10 that of a motor car.

This object I have accomplished by the means which are hereinafter described and claimed, and which are illustrated in the accompanying drawings, in which Fig. 1 is a 15 side elevation of a water circulation pump of a motor car, whose rotary shaft is provided with a governor, and the latter being operatively related to connecting-means adapted to actuate an auxiliary carbureter 20 valve. Fig. 2 is a top plan of the devices of said Fig. 1, including a horizontal fragmental section of a carbureter showing said auxiliary valve mounted in its delivery passage for the fuel to be supplied to an engine. 25 Fig. 3 is a diminished plan diagram, showing an internal combustion engine equipped with my motor governor and connections.

My invention is not restricted to the precise construction and arrangement of parts herein shown and described, nor to the various details thereof, as the same may be modified or rearranged in various particulars without departing from the spirit and scope of my invention, one practical embodiment of 35 which has been herein illustrated and described without attempting to show all of the various forms and modifications in which my invention might be embodied.

My invention pertains particularly to the 40 speed regulation of the motor of a Ford motor car, although it may be adapted for employment on other types of cars. It is suitable to be furnished to farmers and others for use in driving various kinds of 45 machinery, such as mills, rotary saws, feed cutters, by using suitable driving attachments connected to and driven directly by the motor of a car. In these uses, it is desirable that the speed of the motor be automatically regulated to a predetermined limit.

The numeral 29 denotes the motor of a Ford car diagrammatically, having a carbureter 27 in communication with its inlet manifold 37, and having on its crank-shaft a 50 pulley (neither being shown) connected by a belt 34 to a pulley 35 on the rotary fan-shaft

35 in the usual way, the belt 34 being carried around a pulley 4 secured upon the forward end of a rotary pump shaft 3 positioned alongside the left-hand side of the 60 motor.

The motor has the usual water-jacket communicating at the top with a conduit 33 and the top of a radiator 30, and the bottom of the radiator is connected by a hose 32 with 65 a delivery spout 31 on the under side of the casing 2 of a rotary pump, said casing being in communication with the water-jacket and being integral with a frame member 1 having at its forward end a tubular 70 bearing part 5 seating the forward part of the pump-shaft 3 directly back of the said pulley 4.

A collar 6 is secured upon said shaft 3 back of the bearing sleeve 5 and spaced 75 longitudinally from an annularly grooved sleeve 7 which is mounted slidably non-rotatably upon the shaft. At opposite sides the collar 6 and grooved sleeve 7 are connected by means of light, narrow elastic bars 80 9 which carry on their outer faces medially and secured thereto the hemispherical weights 10.

The frame member 1 is spaced sufficiently from the weights 10 as to be cleared by them 85 when rotating at their farthest outward limit of movement. The frame member 1 has a vertically apertured lug 12 projecting part way toward the annular groove 8 of the sleeve 7, its aperture seating a short 90 vertical rock-shaft 13 having its upper part bent at a right angle and terminating in a flattened lozenge-shaped contact head 11 seated in said annular groove 8 in a position to engage either annular rim thereof 95 when the sleeve 7 is moved longitudinally of the shaft 3 by the operation of the centrifugally acting weights 10 when the shaft 3 is in rotation. The lower end of the rock-shaft 13 is bent into a crank 14 whose termination is seated loosely in the rear eye 15 of a connecting-rod 16 directed forwardly.

A horizontally apertured lug 20 projecting from the front part of the motor seats a transverse rock-shaft 19, being a rod with upturned end cranks 18 and 21, the crank 18 being loosely received in the forward end eye 17 of the connecting-rod 16. The other crank 21 is loosely received in the forward end eye 22 of another connecting-rod 23 positioned alongside the opposite side of the motor 29.

A portion of the carbureter delivery neck 27 is shown in Fig. 2. In this neck is shown in plan the usual throttle-valve 28 of the butterfly type adapted as usual to be manually set at a desired angle in more or less restricting the fuel passage of said neck. I have inserted a junction-body 36 between said carbureter neck 27 and the inlet-manifold 37, and have provided a rock-valve 26 in said junction-body having an upwardly projecting stem 25 upon whose outer and upper end is secured a crank 24 with pin seated loosely in a rear end eye of the side connecting-rod 23.

I do not claim the rotary pump 2 adapted to force water circulation from and to the water jacket of the motor through said radiator 30, but it is my intention to utilize the pump shaft 3 to carry the governor shown to thus control by convenient means the auxiliary carbureter valve 26 to thus vary the fuel supply of the motor in the automatic regulation of the speed thereof as predetermined in a limit fixed by the previous setting or adjustment of the throttle-valve 28. The motor may then be employed in operating machinery through the medium of appropriate driving connections to the crank-shaft of the motor.

The operation of the governor will be apparent in its action upon the above described connections to the valve 26, to variably restrict the delivery of fuel through the hollow body 36 to the inlet manifold 37.

Having described my invention, what I claim as new, and desire to secure by Letters Patent, is:

The combination with a motor having an inlet manifold, a carbureter in communication therewith, and a rotary pump shaft driven by said motor, said carbureter having a throttle-valve for fuel delivered to the manifold and also having a rock-valve succeeding the throttle-valve in further controlling the delivery of fuel to the manifold, a centrifugal governor mounted on said shaft, a rock-shaft having a crank moved to and fro by a moving element of the governor, and linking connections between said rock-shaft and the second-mentioned rock-valve, whereby the governor acts to control the rocking of said valve automatically up to a limit of delivery of fuel thereby predetermined by the adjustment of position of said throttle-valve.

In testimony whereof I affix my signature.

WILLIAM HUSMAN.
